(57) **CLAIM**

The ornamental design for an auto-attendant self-service terminal, as shown and described.

DESCRIPTION

FIG. 1 is a perspective view of an auto-attendant self-service terminal showing our new design, with portions of the auto-attendant self-service terminal being shown in phantom as environmental structure; and,

FIG. 2 is a front view thereof.

Broken lines show environmental structure that forms no part of the claimed invention. The top, bottom, left side, right side, and rear views only show environmental structure and thus are not provided.
